DESIGN FOR A DINNER CUP

Helen A. Roberts, Buffalo, N. Y.

Application January 26, 1948, Serial No. 144,025

Term of patent 14 years

(Cl. D44—9)

To all whom it may concern:

Be it known that I, Helen A. Roberts, a citizen of the United States and residing in the city of Buffalo, in the county of Erie and State of New York, have invented a new, original, and ornamental Design for a Dinner Cup, of which the following is a specification, reference being had to the accompanying drawings, forming part thereof.

In these drawings:

Fig. 1 is a top plan view of a dinner cup, embodying my new design.

Fig. 2 is a side elevation thereof viewed from the handle side of the cup.

Fig. 3 is a side elevation thereof viewed from the left-hand side of Fig. 2.

Fig. 4 is a side elevation thereof viewed from the right-hand side of Fig. 2.

Fig. 5 is a bottom plan view thereof.

I claim:

The ornamental design for a dinner cup, as shown.

HELEN A. ROBERTS.
